UNITED STATES PATENT OFFICE.

HENRY L. HOFFMANN, OF NEW YORK, N. Y., ASSIGNOR TO WESTERN ELECTRIC COMPANY, INCORPORATED, OF NEW YORK, N. Y., A CORPORATION OF NEW YORK.

MACHINE-SWITCHING TELEPHONE-EXCHANGE SYSTEM.

Application filed December 24, 1920. Serial No. 433,026.

To all whom it may concern:

Be it known that I, HENRY L. HOFFMANN, a citizen of the United States, residing at New York, in the county of New York, State of New York, have invented certain new and useful Improvements in Machine-Switching Telephone-Exchange Systems, of which the following is a full, clear, concise, and exact description.

10 This invention relates to machine switching telephone exchange systems wherein the substation lines are provided with coin boxes, and wherein it is necessary to collect or refund deposited coins over toll switching trunks from a toll operator's position. It is an improvement upon the system shown and described in the application of Ray L. Stokely for machine switching telephone exchange systems, Serial No. 412,795, filed 20 September 25, 1920. In the system of that application, special coin collect trunks must be provided from the toll position to the different automatic offices having coin lines, and the number of the particular toll switching trunk used by the toll operator in extending the connection to the automatic office is dialed over one of such special trunks; that is to say, the toll operator after having built up the connection over the conversational toll switching trunks, plugs into 30 the jack of one of these special trunks leading to the distant automatic office through which the connection to the called line extends, this trunk terminating in a special connector at such automatic office. The toll operator by means of the dial in her special cord circuit then sets such connector onto multiples of the used toll switching trunk in the automatic office. She can then by means 40 of collect and refund keys in such cord impress current on the toll switching trunk and thence to the called line to operate the polarized magnet in the coin box to collect or refund the deposited coins.

45 In the present arrangement the relays at the automatic office which apply the coin current to the substation line are operated from the toll position directly over the two-wire inter-office conversational toll switching trunk itself, thus eliminating the special coin collect trunks and the special connectors referred to, and also eliminating the extra dialing operation of the toll operator to set the special connectors.

50 More specifically an alternating current relay is bridged across the toll switching trunk at the automatic office and is operated by a circuit closed by the toll operator and including the toll switching trunk. This relay in operating energizes a relay which may be called the coin current applying relay to extend a charging battery of relatively high potential to the toll trunk, and thence to the connected subscriber's line to operate the polarized magnet in the coin box to collect the deposited coins. If on the other hand the coins are to be refunded, the operator in addition to impressing alternating current on the trunk also causes a direct current bridge including a retardation coil to be placed thereacross at her position. The coin current applying relay in operating in either case prepares a circuit for a shifting relay, the function of which relay is to transfer the connections from the charging source to the refund source. This circuit is only closed however if the operator has closed the direct current bridge referred to at her position, and under these conditions the shifting relay operates. The coin current applying relay thus impresses current from the refund source to the toll trunk and thence to the connected line to operate the polarized magnet in the coin box to refund the deposited coins.

55 Referring to the drawings, Figs. 1 and 2 show a toll cord circuit and part of a trunk circuit outgoing from the toll board to a full mechanical or automatic office, Fig. 3 shows the relay and repeating coil equipment associated with the toll transmission selector, Fig. 4 shows the toll transmission selector, and Fig. 5 shows a combination toll and local connector.

60 Referring first to Fig. 1, this drawing shows a cord circuit at the toll operator's position. The left-hand side of this circuit will be called the toll end and the right-hand side will be called the toll and trunk end. In general, the operation is as follows. The operator answers an incoming call by inserting the plug T of the toll end in the answering jack J. If the called subscriber is located in a nearby automatic exchange, the call is completed by inserting the plug TT of the trunk and toll end in a toll switching trunk jack TSJ. The operator then actuates the dialing and monitoring key DK which causes the relay B-34 to operate, 65 which in operating energizes a monitoring

relay (not shown) to place the operator's telephone set in a monitoring position on the cord. The operator now turns the dial D for the first digit of the wanted number. 5 The dial in moving out of its normal position short circuits the relay B-34 permitting the relay E-72 to operate. Relay E-72 in operating locks itself to battery and transfers the tip of the plug TT 10 through the impulse springs of the dial D to the battery. The dial, in returning to normal, interrupts the battery to the tip of the plug causing the impulse relay A-2 of the trunk circuit of Fig. 2 to operate in- 15 termittently, the number of times depending upon the digit involved. This impulse relay, in thus operating, causes the setting of the incoming selector (Fig. 3) at the distant automatic office which thereupon automatically picks out an idle trunk in the selected level. This trunk includes the equipment shown in Fig. 3 and terminates in the selector shown in Fig. 4. When the operator has turned the dial for all the digits in- 20 volved which causes the last switch or connector (Fig. 5) to be set on the desired line, she restores the monitoring DK. If the called line is not busy the trunk and toll supervisory lamp 100 lights as a ringing 25 signal, whereupon the operator by depressing ringing key RK causes the connector to start the ringing of the called line, which ringing continues automatically until the called party answers, whereupon the ringing current is cut off and the lamp 100 is 30 extinguished. When the called subscriber replaces his receiver, this lamp again lights as a disconnect signal.

If the called line is busy or if one of the 40 selectors had failed to find an idle trunk, the lamp 100 will flash, the frequency of the flashes depending upon the busy condition encountered. The toll operator in response to the flashing of the lamp removes the plug 45 TT of the trunk and toll end of the cord from the toll switching jack TSJ, but before removing the toll plug T from jack J, the operator by means of her ringing key R'K', rings on the toll line terminating at 50 the jack J to notify the distant calling operator that the line is clear. If the distant operator rings first, however, the toll supervisory lamp 101 lights and when the operator actuates listening key LK, or pulls out 55 the plug T, this lamp is extinguished.

If the called subscriber can be reached only over a toll line terminating at a toll position at a distant office, the intermediate toll operator inserts the plug TT of the trunk 60 and toll end in a toll line jack leading to such distant office and by means of her ringing key RK rings out over the toll line to signal the distant operator at such office having access to the line of the caller sub- 65 scribed who then completes the connection.

When the calling toll operator applies ringing current to the trunk at the termination of the conversation, the toll supervisory lamp 101 lights until the listening key LK is operated or the connection is taken down. 70 The keys K and K' serve, when operated, to disconnect either end of the cord from the operator's telephone set when the operator is talking on the other end.

More in detail, when the plug T of the toll end is inserted in toll answering jack J, relay E-156 operates, in turn operating relay B-162. Relay B-162 opens the circuit of relay E-162 preventing the toll supervisory lamp 101 from lighting. When the plug TT of the trunk and toll end is inserted in toll switching trunk jack TSJ leading to an incoming selector at an automatic office, relay E-99 operates in series with relay E-155 and the right winding 85 of relay E-156. Relay E-99 disconnects the busy test equipment of the operator's telephone set from the tip of the cord and connects the tip of the cord through to the ringing key. Relay E-155 is marginal and 90 does not operate at this time on account of the high resistance in the sleeve of the toll switching trunk circuit, and thus leaves the calling supervisory relay B-43 bridged across the trunk. Ringing current applied by a distant toll operator operates the alternating current relay A-196 which releases relay B-162. The latter relay in releasing lights the toll supervisory lamp 101 and operates relay E-162 in parallel with the 100 lamp. Relay E-162 locks up under the control of the listening key LK and relay E-156 so that the lamp remains lighted after the ringing ceases and the relay B-162 is re-operated through the back contact of relay A-196. The lamp 101 may be extinguished by operating the listening key which releases relay E-162 or by taking down the connection which releases relays E-156 and E-162. Relay E-162 is made 110 slow in operating to guard against the possibility of lamp 101 being lighted by Morse impulses. Relay A-196 may be operated for a short time by Morse impulses and release relay B-162 momentarily, but 115 the slow operating feature of the relay E-162 will give relay B-162 time to re-operate before the relay E-162 operates and locks. When both ends of the cord are inserted in toll line jacks terminating at toll 120 board positions, the marginal relay E-155 disconnects the calling supervisory relay B-43 from the cord circuit. If, on a through toll connection of this character the splitting key K' is operated to disconnect the trunk and toll end TT from the operator's telephone set, relay B-43 is 125 bridged across the trunk and toll end so that it will operate when ringing current is received from the trunk and toll end and 130

flash the lamp 100. When the splitting key K' is in its normal position this bridge for relay B-43 is opened.

Referring now to Fig. 2 which represents a toll switching trunk over which a connection is extended to an automatic exchange, relay C-2 operates over its right hand winding when the operator inserts the plug TT into jack TSJ and by attracting its armature closes a loop circuit leading to the impulse relay of the incoming selector at such exchange, which selector being well known is not shown. It may be of the type shown in application of R. L. Stokely, Serial No. 412,795, filed September 25, 1920. The brushes 300, 301, 302 and multiples 303, 304, 305 indicate such selector. When the dialing key DK is thrown and the dial is operated, relay A-2 operates, connecting relay I-2 across the loop leading to the impulse relay of the incoming selector at the automatic office. Relay I-2 in operating causes slow relay D-2 to operate, which relay shunts the left hand winding of relay C-2 whereupon the latter relay releases, the circuit through its right hand winding being opened when relay E-72, Fig. 1, operates as the dial is moved out of its normal position. Relay D-2 in operating operates relay E-2 which locks up to the ground at the inner left contact of relay B-2, now energized. Relay E-2 at its outer left contact locks up relay D-2, independently of its original energizing circuit which leads over the front contact of relay I-2. The dial in restoring intermittently operates relays A-2 and I-2, relay A-2 intermittently opening the loop circuit to the impulse relay of the incoming selector and relay I-2 alternately opening and closing a shunt path around relay D-2. If, during the operation of building up a connection, one of the selectors fails to find an idle trunk in the selected group, it opens the loop circuit including relay I-2. Relay I-2 in closing its back contact permanently shunts out relay D-2. Relay D-2 in closing its right hand contact operates relay H-2. Relay H-2 locks up and connects interrupted battery of 60 impulses per minute to the winding of relay C-2 in shunt of the resistance 200. Relay B-43 in the cord (Fig. 1) follows these impulses and flashes the supervisory lamp 100 to indicate to the operator the failure to find an idle trunk.

In case the called line is busy, interrupter 233 is connected in circuit to flash the lamp 100 at a different rate to indicate to the operator the busy condition of the selected line.

In case the called subscriber's line is found to be idle by the connector (Fig. 5) this condition causes the polarized relay F-2 to operate and cause lamp 100 to remain steady.

ily lighted as a ringing signal when the operator restores the key DK. Relay F-2 in operating also energizes relay G-2 which cuts the trunk through, thus disconnecting the relays C-2 and A-2 from the circuit leading back to the toll operator's position. 70

Having described in a general manner the operation of the system, a call will now be traced in detail.

The toll operator, having been informed of the number of the wanted line and assuming this line to be in a nearby automatic exchange, tests for an idle trunk by touching the tip of her plug TT to the sleeve of the jack TSJ of the toll switching trunk in the well known manner, and if she does not receive a click in her receiver she inserts the plug TT into the toll switching trunk jack TSJ. The following circuit is thereupon closed to operate relays E-99, 85 (Fig. 1) and B-2 (Fig. 2): free pole of battery, relays E-99, E-155, right winding of relay E-156, sleeves of the plug and jack, relay B-2 to ground. Relay E-155 does not operate in the circuit, as stated. 90 Relay E-156 is operated due to plug T being inserted in jack J.

ductor 103, tip of the plug 11, tip of the jack TSJ, outer normal contact of relay 130, conductor 131, armature 204 and back contact of relay G-2, conductor 213 and relay A-2 to ground. Relay A-2 is marginal and does not operate in this circuit. Relay C-2 in attracting its armature closes the following bridge to operate the impulse relay of the incoming selector at the automatic office, conductor 205, conductor 206, 130

outer left hand armature and back contact of relay H—2, conductor 207, armature and front contact of relay C—2, left hand winding of relay C—2, conductors 208 and 209, 5 inner right armature and front contact of relay B—2, conductor 210, polarized relay F—2, conductor 211, conductor 212. The operator now throws the dialing and monitoring key DK, whereupon a circuit is 10 closed to operate relay B—34, Fig. 1, which in attracting its armature closes a circuit to connect the operator's head set across the cord. She now rotates the dial D for the first digit of the wanted number. The closure 15 of the contact 104 of the dial as the dial moves off normal shunts the relay B—34, which permits the marginal relay E—72 to operate. Relay E—72 in attracting its right hand armature locks itself to 20 ground at a contact of the dialing key DK which when actuated remains in its operated position until manually restored by the operator. Relay E—72 in closing its left-hand contact opens the bridge containing relay 25 B—43 and connects the free pole of the battery through the impulse contact 108 of the dial to the tip of the plug. The opening of the said bridge opens the circuit heretofore traced through the right hand winding of 30 relay C—2. Marginal relay A—2 now operates in series with the impulse contact of the dial, the circuit being as follows: free pole of battery, resistance 109, impulse contact 108, left hand armature and front contact 35 of relay E—72, conductor 103, tip of the plug TT, tip of the jack TSJ, outer normal contact of relay 130, conductor 131, armature 204 and back contact of relay G—2, conductor 213 and relay A—2 to 40 ground. Relay A—2 in attracting its left hand armature bridges relay I—2 across the tip and ring of the trunk in parallel with the left hand winding of relay C—2. Relay I—2 in attracting its armature closes 45 a circuit to operate relay D—2 as follows: free pole of battery, resistance 214, conductor 215, relay D—2, conductor 216, right armature and front contact of relay I—2, conductor 217, contact 218 of relay G—2 to 50 ground. Relay D—2 in attracting its left armature short circuits the left hand winding of relay C—2 which thereupon releases, thus opening one of the bridges to the impulse relay at the incoming selector and 55 leaving bridged across the circuit only relay I—2. This bridge may be traced as follows: conductors 205 and 206, outer left hand armature and back contact of relay H—2, conductor 207, conductor 208, relay I—2, 60 left hand armature and front contact of relay A—2, conductor 211, conductor 212. Relay D—2 at its right armature and front contact closes the following circuit to operate relay E—2: free pole of battery, relay 65 E—2, conductor 220, right armature and

front contact of relay D—2, conductor 221, conductors 222 and 228, inner left armature and front contact of relay B—2 to ground. Relay E—2 in attracting its inner right armature locks itself to grounded conductor 70 222. The function of this relay will be later described. Dial D, Fig. 1, in returning to normal, interrupts at its impulse contact 108 the circuit of the impulse relay A—2, Fig. 2, which at its left armature 75 interrupts the circuit of the impulse relay of the incoming selector a number of times corresponding to the first digit of the wanted number. The incoming selector IS is thus set to the desired level and then automatically picks out an idle toll transmission selector shown in Figs. 3 and 4. The terminals of this selector are designated 303, 304, 305.

The seizure of the toll transmission selector, Fig. 4, with which the relay and repeating coil equipment of Fig. 3 is associated, causes the closure of the following circuit for impulse relay A—4, Fig. 4, of the toll transmission selector: free pole of battery, right hand winding of relay A—4, conductor 400, conductor 306, outer left armature and back contact of relay B—3, conductor 307, contacts of relays F—3, and H—3, conductor 308, upper left-hand winding of repeating coil 309, conductor 325, multiple terminal 303, brush 300, conductor 212, conductor 211, left armature and front contact of relay A—2, relay I—2, conductors 208, 207, outer left hand armature and back contact of relay H—2, conductors 206, 205, brush 301, multiple terminal 304, conductor 326, lower left hand winding of the repeating coil, conductors 311, 312, contacts of relays H—3 and F—3 and B—3, conductor 313, conductor 401, through the left winding of relay A—5 to ground at the lower normal contact of the switch 402 which is operated only on the eleventh rotary step of the transmission selector. The impulse relay A—4 in attracting its right armature energizes slow relay B—4. This relay in attracting its left armature applies a ground over the sleeve wires 451 and 314 to multiple 305 to cause this trunk to test busy and to hold up the release relay of the incoming selector in the well known manner. When the relay B—4 operates it closes at its right hand armature the following circuit for relay D—3 of the relay and repeating coil circuit, Fig. 3: ground, right armature and front contact of relay B—4, conductors 403 and 418, conductor 404, conductor 405, contact 406 of relay D—4, conductor 407, 315, outer right hand armature and back contact of relay F—3, conductor 316, relay D—3 to free pole of battery.

The second operation of the dial by the operator transmits the second digit of the called line causing relay A—2, Fig. 2 to open 130

and close the impulse circuit for the relay A-4, which in vibrating its right hand armature transmits impulses over the following circuit to the vertical magnet 408 of the toll transmission selector: grounded right armature and back contact of relay A-4, inner armature and front contact of relay B-4, conductor 409, armature 410 and back contact of relay D-4, conductor 411, slow relay C-4, magnet 408 to free pole of battery. The brushes of the toll transmission selector are thus elevated to the desired level. When the dial returns to normal and maintains the relay A-2 energized, relay A-4 remains energized and, after a slight interval, slow relay C-4 releases. When the relay C-4 operated on the first impulse and the selector took its first step, relay E-4 operated over the following circuit: free pole of battery, relay E-4, upper contact of off normal switch 415, conductor 416, armature and front contact of relay C-4, conductor 417, conductor 418, conductor 403 to ground at the right armature and front contact of relay B-4. In attracting its inner armature, relay E-4 locks itself to the upper armature and back contact of slow relay F-4, this circuit including the armature and back contact of rotary magnet 419. Upon the cessation of the impulses and the release of the slow relay C-4, the circuit of the rotary magnet is closed as follows: free pole of battery, magnet 419, outer armature and front contact of relay E-4, normal contact of relay C-4, conductor 417, conductor 418, conductor 403, right armature and front contact of slow relay B-4 to ground. The rotary magnet advances the brushes onto the terminals of the first trunk and at the end of its stroke opens the locking circuit of the relay E-4 which releases, opening the circuit of the rotary magnet. If the trunk is busy, relay E-4 again energizes over the following circuit: free pole of battery, relay E-4, upper contact of switch 415, conductor 416, conductor 420, armature and back contact of rotary magnet 419, conductor 421, conductor 422, back contact and armature 423 of relay D-4, conductor 424, lowermost armature and back contact of relay F-4, conductor 425, test brush 426 to ground on the test multiple 427. Relay E-4, in attracting its inner armature again locks up through the upper armature and back contact of relay F-4 and at the other armature again closes the circuit of the rotary magnet which advances the brushes to the next trunk and at the end of its stroke opens the locking circuit of relay E-4 which in retracting its armature opens the circuit of the rotary magnet 419.

Assuming now that the selector has failed to find an idle trunk. In that event on the eleventh rotary step, switch 402 is operated by the shaft of the selector and opens the

loop circuit including impulse relay A-4 and relay I-2 (Fig. 2). The opening of the loop circuit causes relay I-2 (Fig. 2) to be permanently deenergized. When the operator has transmitted all the digits, relay A-2 in remaining attracted and the relay I-2 being inert, the following short circuit is closed about the slow relay D-2 to cause the same to release: free pole of battery, resistance 214, right hand armature and front contact of relay A-2, armature and back contact of relay I-2, conductor 217, contact 218, to ground. It will be understood that relay D-2 is slow to release as shown and holds up during the impulses. Relay D-2 in retracting its right armature operates relay H-2 over the following circuit: free pole of battery, relay H-2, conductor 290, right armature and back contact of relay D-2, conductor 220, inner right hand armature and front contact of relay E-2 to ground on conductor 222. Relay H-2 in attracting its inner left armature locks itself up to grounded conductor 222 and in attracting its inner right armature connects interrupter 223 to the inner left hand armature and front contact of relay E-2 to shunt the resistance 200 to cause supervisory relay B-43 in the cord circuit to flash the trunk and toll supervisory lamp 100 at the rate of 60 flashes per minute when the operator restores the dialing key DK which she does after transmitting all the sets of impulses. This rate of flashing will indicate to the operator that one of the switches has encountered a busy trunk group whereupon she will pull out the plug and will then wait and set up the connection later. Although the interrupting machine 223 is connected to the front contact of relay E-2 as soon as relay D-2 releases and relay H-2 operates, this is not effective to flash the lamp until the operator, after having turned the dial for the last time, releases her dialing key DK, Fig. 1. The opening of the lowermost contact of this key releases relay E-72 which in retracting its left armature again closes the loop circuit including the right hand winding of relay C-2, Fig. 2, and the relay A-2, Fig. 2 and B-43 (Fig. 1). The relay H-2 in attracting its outer left armature interposes a break in the loop circuit leading to the selector (Fig. 4) thus preventing the subsequent impulses from passing to the selector circuit.

If, however, an idle trunk is found by the selector (Fig. 4), relay D-4 operates over the following circuit: free pole of battery, relay E-4, upper contact of switch 415, conductor 416, conductor 420, armature and back contact of magnet 419, conductors 421, 422, relay D-4, upper normal contact of switch 402, conductors 430, 403 to ground at the right armature and front contact of

relay B-4. Relay E-4 is marginal and does not operate in this circuit in series with the relay D-4. Relay D-4 in attracting its armatures 431 and 432 extends the talking conductors through to the talking brushes 433 and 434. The attraction of the armature 423 of relay D-4 grounds the test brush 426 and consequently test multiple 427 of the selected trunk, causing the same tact of relay D-3, resistance 321, upper right hand winding of repeating coil 309, upper armatures and back contacts of relays M-3 and K-3, tip conductors 322, 447, armature 431, and front contact of relay D-4, conductor 448, brush 433, multiple 449, tip conductor 450, conductor 510, upper armature and back contact of relay K-5, conductor 511, conductor 512, lower winding of relay A-5 to ground. Relays J-5 and A-5 operate in this circuit, the former at its innermost right armature closing a locking circuit for itself as follows: free pole of battery, right winding and right innermost armature and front contact of relay J-5, conductor 514, conductor 531, conductor 515 to ground at the armature 516, and front contact of slow relay B-5 which is energized upon the energization of the impulse relay A-5. Relay B-5 grounds the sleeve wire 517, leading to the test multiples in the local selectors, this circuit leading from grounded armature 516, conductor 515, to conductor 517. The return of the dial to normal transmitting the tens digit after the operation of transmitting the hundreds digit of the wanted number interrupts the circuit of relay A-2, Fig. 2 which in turn interrupts the circuit of the impulse relay A-5, Fig. 5 which in vibrating its armatures transmits impulses to the vertical magnet 518 of the connector over the following circuit: free pole of battery, magnet 518, slow relay 519, right contact of off normal switch 520, conductor 521, lower armature and front contact of relay B-5 to ground at the armature and back contact of the impulse relay A-5. At the first step of the connector, the off normal springs 520 are shifted and the succeeding impulses are transmitted by way of the upper armature and front contact of relay 519 and the contact 522 now closed at the off normal springs 520. The selector brushes are thus lifted to the desired level and upon the cessation of the impulses, impulse relay A-5 remains energized and relay 519 in series with the vertical magnet releases preparing the circuit of the rotary magnet 523. The units impulses pass through the back contact of the impulse relay A-5, lower armature and front contact of relay B-5, conductor 521, off normal contact 522, upper armature and back contact of slow relay 519, conductor 524, left armature and back contact of relay G-5, conductor 525, uppermost armature and back contact of relay H-5, rotary magnet 523 to free pole of battery. The connector is thus stepped around into engagement with the desired line.

If this line is idle, potential is present on its test multiple 526 through the cut off winding of the line switch in accordance with well-known systems such as that disclosed

10 70 75 80 85 90 95 100 105 110 115 120 125 130

15 20 25 30 35 40 45 50 55 60 65

in Patent 1,159,855, issued November 9, 1915, to T. G. Martin, and the following circuit is closed to operate relay H-5: multiple 526, brush 527, conductor 528, right hand 5 armature and back contact of relay E-5, conductor 529, upper winding of relay H-5, conductor 530, right hand armature and back contact of relay G-5, conductor 531, conductor 515, armature 516 of relay B-5 to ground. Relay H-5 in attracting its armature 532 locks itself to the grounded sleeve wire 550 and extends this grounded conductor over conductor 533, middle right armature and front contact of relay J-5, conductor 534 to the relay K-5. Relay K-5 in attracting its armature 502 disconnects the grounded sleeve wire 550 from the control lead 500 leading back to the relay D-3, Fig. 3 of the relay and repeating coil 10 equipment circuit. Relay D-3, therefore releases and in retracting its right hand armature operates relay F-3, Fig. 3, over the following circuit: free pole of battery, relay F-3, right armature and back contact of relay D-3, conductor 323, conductor 450, armature 423 and front contact of relay D-4, conductors 418, 403 to ground at the right armature and front contact of relay B-4. Relay F-3 in attracting its 15 outer right armature closes a substitute ground to hold up the slow relay F-5 to prevent ringing from occurring at this time: ground, right hand armature of relay E-3, conductor 324, right armature and back contact of relay B-3, outer right armature and front contact of relay F-3, control conductors 315, 407, contact 435 of relay D-4, conductor 438, brush 439, multiple 440, conductor 441, conductor 500, front contact and armature 535 and lower winding of relay F-5 to free pole of battery. Relay F-5 was energized upon the first impulse to the vertical magnet, this circuit being as follows: free pole of battery, lower winding of relay F-5, lower armature and front contact of slow relay 519, innermost right hand armature and front contact of relay J-5, conductor 514, conductors 531 and 515 to ground at the upper inner armature and front contact of relay B-5. When energized relay F-5 locked by way of its armature 535 and front contact, conductor 501, armature 502 and back contact of relay K-5 to grounded sleeve wire 550. Consequently, the operation of relay K-5 to cause the reversal of direction of the current flow in the loop leading back to the toll operator's position opened the circuit of slow relay F-5 and unless a substitute circuit was provided for holding it up the ringing operation would automatically take place. This is prevented by applying a substitute ground as described to the control conductor 500 over the circuit traced to hold the relay F-5 until the operator, by depressing a key as will be explained, releases it to start the automatic ringing operation. The release of the relay D-3 and the consequent energization of relay F-3 as described reverses the direction of current flow in the talking 70 conductors leading back to the operator's position. After having turned the dial for the last digit, the operator restores her dialing key DK which releases relay E-72 as described which disconnects the dial from the tip of the plug, causing the release of the relay A-2, Fig. 2 and the closure of an energizing circuit for relays C-2 and B-43, through the right hand winding of relay C-2, relay B-43 and relay A-2. Relay 75 A-2 it will be remembered, releases under this condition and in retracting its left armature opens the bridge to the distant office including relay I-2 leaving only the polarized relay F-2 bridged across the trunk 80 from upper talking conductor 212, Fig. 2, conductor 211, polarized relay F-2, conductor 210, inner right armature and front contact of relay B-2, conductor 209, conductor 208, left hand winding of relay C-2, 85 armature and front contact of relay C-2, conductor 207, outer left armature and back contact of relay H-2, conductors 206 to lower talking conductor 205. The reversal of the direction of current in the talking 90 conductors due to the operation of relay F-3 (Fig. 3) causes the relay F-2 to operate, closing the following circuit for relay G-2: free pole of battery, relay G-2, conductor 224, contact 225 of relay F-2, conductors 226, 227, 228, inner left armature and front contact of relay B-2 to ground. Relay G-2 locks itself up over the following 95 circuit: free pole battery, relay G-2, conductor 224, conductor 229, front contact and armature 230, of relay G-2, conductor 231, conductors 227, 228 to ground at the inner left hand armature of relay B-2. Relay G-2 connects the talking conductors of Fig. 2 through to the talking conductors 100 of Fig. 1 whereupon the calling supervisory relay B-43 operates in series with the relay A-4, Fig. 4, and lights the supervisory lamp 100 as a ringing signal to the toll operator. Relay G-2 Fig. 2 cuts off the bridge including relays C-2 and A-2. Relay C-2 opens the bridge containing relay F-2. The operator now operates her ringing key RK which impressed alternating current upon the talking conductors and operates the alternating current relay C-3 in bridge of the trunk (Fig. 3) which in attracting its armatures operates the relay E-3. The polarized relay S-3 is also bridged across the trunk, Fig. 3, but the 110 low frequency 16 to 20 cycle ringing current will immediately operate relay C-3 which will by attracting its outer left armature open the bridge containing relay S-3. Relay S-3 is arranged to respond to rela- 115 120 125 130

tively high frequency alternating current only, say 135 cycles. Relay S-3 will not therefore release relay R-3 which is now energized from ground on the sleeve wire 5 314. Relay R-3 is at this time holding open the circuit of relay H-3 for a purpose which will later appear. To guard against a momentary opening of the back contact of relay S-3 releasing relay R-3, relay 10 R-3 is made slow to release as shown. Relay E-3 in attracting its right armature opens the circuit heretofore traced, which has been holding relay F-5, Fig. 5, energized. Relay F-5 in retracting its armature 15 537 connects ringing current to the called line through its own upper winding. This ringing current is automatically continued until the called party removes his receiver, resulting in the increase in the current 20 through the upper winding of relay F-5 causing the same to operate removing the ringing current. The attraction of the armature 535 of this relay again closes the locking circuit for the same over control conductor 500. The extension of the tip and ring conductors by relay F-5 to the called line operates relay A-3 over the winding of which talking current is fed to the called line. Relay A-3 in operating energizes 25 relay B-3 which in attracting its right hand armature applies ground to the control conductor 315 to hold up relay F-5, Fig. 5. Relay B-3 in attracting its left armatures closes a bridge across conductors 306, 313 30 to hold up relay A-4, and opens the connection of battery through the windings of relay A-4, Fig. 5, to the talking conductors, leading back to the operator's position which causes the deenergization of supervisory relay B-43. This relay in retracting its armature 35 extinguishes the supervisory lamp 100 which notifies the operator that the subscriber has responded. Talking current is fed to the called line over the windings of relay A-3 and the repeating coil 309. This 40 talking circuit is a standard repeating coil transmission circuit used in long distance connections. Talking current is fed to the other line from the distant exchange. During 45 conversation the trunk leading from the left hand windings of repeating coil 309 through the right hand winding of the repeating coil (not shown) at the distant office is dry, in accordance with standard practice. 50 The operator may now request the subscriber at the substation shown in Fig. 5 to deposit the necessary coins in the coin box which may be of the type shown in said Patent 1,043,219, issued November 5, 1912 to O. F. Forsberg. These coins in passing 55 through the box strike gongs whereby the operator is informed of the denominations of the coins inserted. When she is satisfied that the proper coins have been deposited she picks up her plug P Fig. 1 and 60 inserts it into the jack 133, and closes the left contacts of switch 135 which grounds the ring of the plug, this resulting in the energization of relay 134. Relay 134 in operating energizes relay 130. Relay 130 in 65 operating applies high frequency alternating current, which may be of 135 cycles per second, to the trunk 131, 137, which operates the alternating current relay S-3, Fig. 3. This relay in operating removes the shunt 70 from about relay G-3 which in operating grounds conductor 306 leading to the winding of relay A4, Fig. 4, which is connected to battery. This is to prevent the release 75 of the connection if the subscriber should hang up his receiver at this time since relay 130, Fig. 1, in operating opens the loop circuit over which the relay A4 was held over the cord. Alternating current relay S3 in operating releases slow marginal relay R3, which in closing its back contact energizes relay H3, this circuit including armature and front contact of relay F3 now energized. Relay H3 in attracting its inner right armature operates relay K3 and in attracting its outer right armature extends the source of 110 volt collect current through the front contacts of the relay K3, to the trunk conductors 322, 318. This current passes over the talking 80 conductors, Figs. 4 and 5 to ground through the polarized magnet P-5, Fig. 5. When the polarized magnet P-5 operates and collects the coins, it opens the contact 538 in the coin box to remove the polarized magnet 85 from the talking circuit. 90 If on the other hand the deposited coins are to be refunded, the operator closes the right contacts of switch 135, Fig. 1. This not only grounds the sleeve of the plug P 95 but also the tip of the plug, resulting not only in the operation of the relays 134 and 130, but also relay 150 which in operating bridges a retardation coil 138 across the trunk conductors 131 and 137. As before 100 the high frequency alternating current from the source 136 causes the operation of the relay H-3. Due however, to the presence of the bridge containing retardation coil 138, Fig. 1, the shifting relay N3 operates, its 105 circuit including the left-hand armatures and front contacts of relay H3, the talking conductors, Figs. 2 and 1, and the bridge referred to. Relay N-3 shifts the conductor 339 leading to the front contact of the relay H-3 from the collect source of positive current to the refund source of negative current. Consequently refund current is 110 transmitted over the line to operate the polarized magnet P-5 in the coin box in the substation in the other direction to refund the coins and open the contact 538. The alternating current relay C-3 which will be 115 remembered operates to cause the ringing operation of the connector to take place, will 120 125 130

not operate on the 135 cycle current for the reason that it is mechanically slow to operate and its electrical characteristics are such that it will not respond to such high frequency alternating current.

- Assuming now that the desired line when selected by the connector is busy. In that case the test multiple 526 Fig. 5 is grounded. When test wiper 527 is set on the busy multiple 526, ground is extended over brush 527, conductor 528, contact 540 of relay E-5, conductor 541, armature 542 and back contact of relay H-5, conductor 543, relay G-5 to free pole of battery. Relay G-5 energizes and when E-5 releases as the units impulses terminate locks itself up over the following circuit: free pole of battery, relay G-5, conductor 543, armature 542 and back contact of relay H-5, conductor 541, make before break contact 544 of relay E-5, right armature and front contact of relay G-6, conductor 531, conductor 515 to ground at the armature 516 and front contact of relay B-5. Relay G-5 in the case of a local call connects busy tone from the source 545 to the calling line. In the case of a toll call this busy tone is not used, a flashing signal being given to the operator instead, as described. Due to the operation of relay G-5 relay H-5 cannot operate. Consequently, relay K-5 is not energized to open the circuit of relay D-3 Fig. 3 as described in the case of an idle line. Inasmuch as relay D-3 remains energized, relay F-3, whose circuit is maintained open at the outer right armature and back contact of relay D-3 is not operated and no current reversal in the trunk leading back to the operator's position occurs. Polarized relay F-2 Fig. 2, is not operated in this case and relay G-2 remains inert. Since the relay E-2 is locked up at this time and relay G-2 is inert, when the operator restores her dialing key DK a circuit is closed from interrupter 233 of 120 impulses per minute to shunt out resistance 200 to cause the supervisory relay B-43 to flash the lamp 100, 120 times per minute, which indicates to the operator that the selected line is busy, whereupon she pulls out the plug TT from the trunk switching jack TSJ which results in the release of all switches and the normal condition of all the apparatus including the various locked up relays.
- During the conversation the called subscriber by moving his hook up and down causes the supervisory lamp 100 at the toll operator's position to flash as in manual practice without releasing the switches.
- This is apparent from the preceding description inasmuch as relay A-3 Fig. 3 is in circuit with the called line and each time it attracts its armature it operates the relay B-3 which removes battery and ground from the trunk conductors leading back to

the supervisory relay B-43 and puts a bridge across the relay A-4 to hold it operated. When the called subscriber replaces his receiver the lamp 100 at the toll operator's position Fig. 1 is lighted. The operator may re-ring the subscriber if necessary if she desires to recall him by actuating her ringing key RK which operates relay C-3 to operate E-3 which in attracting its right hand armature again releases relay F-5 Fig. 5 which initiates the automatic ringing operation. The control of this relay F-5 is removed from the relay E-3 by the attraction of the right armature of relay B-3 when the called subscriber responded and is restored to the relay E-3 and consequently to the operator when the called subscriber replaces the receiver and de-energizes relay B-3.

When the operator desires to break down the connection after the called subscriber has replaced his receiver, she removes the plug TT from the toll switching jack TSJ. This releases relay A-4 Fig. 4 which causes the restoration of all the switches. If, however, the operator pulls out the plug while the called subscriber still has his receiver off the switch hook, the switches are not released.

Assuming, however, that the called subscriber has replaced his receiver, when the operator removes the plug, relay A-4 releases, de-energizing relay B-4. Relay B-4 in retracting its outer left armature removes ground from the sleeve conductor 451 leading over the sleeve conductor 314 to the release relay of the incoming selector IS which thereupon causes release of such selector in the well-known manner. The removal of ground from conductor 403, by the retraction of right hand armature of relay B-4 releases relay D-4 and the retraction of the right hand armatures of relay A-4 and inner left armature of relay B-4 closes the circuit of the release magnet 452 of the toll transmission selector as follows: free pole of battery, magnet 425, lower contact of off normal switch 415, conductor 453, back contact and inner left hand armature of relay B-4 to ground at the right hand armature and back contact of relay A-4. The slow relay F-4 is energized in parallel with the release magnet and opens the circuit to the test brush 426 during restoration at its lowermost armature. At its armature 454 it short circuits the left hand winding of relay A-4. At its upper armature it closes a locking circuit for itself which is opened when the off normal switch assumes its normal position. The opening of the circuit of the tip and ring conductors 510 and 546 causes the release of relays A-5, B-5, J-5, Fig. 5 which results in the closure of the circuit of connector release magnet 546: free pole of battery, magnet 546, left hand contact of off normal switch 520, back contact

and lowermost armature of relay D-5, lower armatures and back contacts of relays B-5 and A-5 to ground. The connector upon reaching normal position restores the 5 off normal switch 520.

The relay M-3 is provided to permit the toll operator to apply ringing current to a selected private branch exchange line to signal the operator thereat. This relay is operated when relay E-3 is operated due to 10 the actuation of the ringing key by the toll operator. In private branch exchange working the called subscriber may hang up his receiver, but due to the bridge at the P. B. X. 15 operator's board the relay A-4 remains operated and thus no disconnect signal is given to the toll operator.

What is claimed is:

1. In a telephone system the combination 20 of subscribers' lines, an operator's position, means including toll switching trunks and automatic switches for extending a call from said position to a subscriber's line, a coin box at the substation of said line having a 25 coin disposal magnet, collect and refund current sources associated with one of said trunks, a coin current applying relay associated with said trunk, an alternating current source at said position, a manual switch 30 at said position for applying alternating current from said source to said trunk to cause the operation of said relay to apply current from one of said sources to the connected substation to operate the coin disposal 35 magnet in one manner, a shifting relay also associated with said trunk, and a manual switch at said position for operating said coin current applying relay and also said shifting relay, the latter substituting the 40 other coin current source to operate the coin disposal magnet in another manner.

2. In a telephone system the combination 45 of telephone lines, a connection comprising toll trunks and automatic switches, a coin box at the substation of the connected line having a coin disposal magnet, a toll operator's position, a pair of coin current sources associated with one of said trunks, a coin current applying relay associated with 50 said trunk, means including a manual switch at said position for operating the same, a shifting relay controlling the association of said sources with said trunk, a circuit for operating the same controlled at alternate 55 contacts of said coin current applying relay and including the trunk leading back to the toll position, and means at said position controlled by the operator for closing the circuit or not, dependent upon which source 60 is to be connected to the connected subscriber's line.

3. In a telephone system the combination 65 of telephone lines, an operator's position, means including toll trunk lines and automatic switches for extending connection to

one of said lines, a coin box at the substation of said line having a coin disposal magnet, collect and refund coin current sources associated with one of said toll trunks, a coin current applying relay associated with said 70 trunk, a shifting relay for controlling the connection of said sources to said trunk, an alternating current source associated with said position, a manual switch for applying alternating current from said source to said trunk to cause the operation of said coin current applying relay to apply current from one of said sources to operate said coin disposal magnet in one direction, a bridge for said trunk, an impedance device 75 therein, and a second manual switch for applying alternating current from said source to said trunk and also closing said bridge thereacross to operate said shifting relay to cause said coin current applying 80 relay to apply current from the other source to said magnet.

4. In a machine switching telephone system, the combination of a number of offices, a toll position at one office, automatic 85 switches and trunks at another office, subscribers' lines terminating in said last office, a two-wire interoffice trunk over which said switches are set to complete a connection to one of said lines, coin boxes at the 90 substations of said lines having coin disposal magnets, sources of collect and refund current at said automatic office, a coin current applying relay at said automatic office operated from said toll position over said 95 two-wire interoffice trunk to cause current from one of said sources to be applied to the coin disposal magnet to operate the same in one direction, a shifting relay at the automatic office, and means controlled by the 100 toll operator including a circuit over said interoffice trunk for also causing the operation of said shifting relay to cause current from the other source to be applied to the coin disposal magnet to operate the same in 105 another direction.

5. In a machine switching telephone system, the combination with a number of offices, a toll position at one office, automatic 110 switches and trunks at another office, subscribers' lines terminating in said last office, a two-wire interoffice trunk over which said switches are set to complete a connection to one of said lines, coin boxes at the substations of said lines having coin disposal 115 magnets, sources of collect and refund current at said automatic office, of a pair of relays at said automatic office, one arranged to shift the connections of said sources, and the other to cause the extension of said connections to the trunk leading to the connected line, a bridge for said trunk, a retardation coil therein, and manual means at the toll office for either applying alternating 120 current to operate said latter relay to cause 125

current from one source to be applied to the connected line, or for applying alternating current and also a bridge containing a retardation coil across the trunk to permit 5 said first mentioned relay also to operate and shift the connections to the other source.

6. In a machine switching telephone system, the combination with a number of offices, a toll position at one office, automatic 10 switches and trunks at another office, subscribers' lines terminating in said last office, a two-wire interoffice trunk over which said switches are set to complete a connection to one of said lines, coin boxes at the substations of said lines having coin disposal magnets, and a source of collect current at said automatic office of an alternating current relay in the trunk at said automatic office arranged when operated to cause the extension 15 of said source to the trunk leading to the connected line, and a key at the toll position for applying alternating current to said interoffice trunk to operate said relay.

7. In a machine switching telephone system, the combination with a number of offices, a toll position at one office, automatic switches and trunks at another office, subscribers' lines terminating in said last office, a two-wire interoffice trunk over which 20 said switches are set to complete a connection to one of said lines, coin boxes at the substations of said lines, coin disposal magnets therein, and a source of collect current at said automatic office, of an alternating current relay in the trunk at said automatic office, a relay operated thereby to cause the extension 25 of said source to the trunk leading to the connected line, and a key at the toll position for applying alternating current to said interoffice trunk to operate said alternating current relay.

8. In a telephone system, an operator's position, a trunk, two alternating current relays bridged thereacross, one adapted to 30 respond to high frequency alternating current only, and the other to low frequency alternating current only, a coin current charging circuit controlled by one relay, and a ringing circuit controlled by the 35 other, sources of current of high and low frequency at said position, and manual means controlled by the operator thereat for impressing current from said sources on said trunk to selectively operate said alternating current relays.

9. In a telephone system, an operator's

position, a trunk, two alternating current relays bridged thereacross, one adapted to respond to high frequency alternating current only, and the other to low frequency alternating current only, a slow-to-release relay, 40 a circuit therefor including a back contact of said high frequency relay, a coin current applying relay, a circuit therefor including a back contact of said slow relay, a relay 45 adapted to be operated by the operation of said low frequency relay to cause ringing current to be applied to the trunk, sources of high and low frequency current at said position, and manual means controlled by 50 the operator for impressing alternating current from said sources to said trunk to selectively operate said alternating current relays.

10. In a telephone system, an operator's 55 position, a distant office, a two-wire trunk leading from said position to said distant office, two alternating current relays bridged across said trunk at the distant office, one adapted to respond to high frequency alternating current only, and the other to low frequency alternating current only, a coin current charging circuit controlled by one relay, and a ringing circuit controlled by the other, sources of alternating current of 60 high and low frequency at said position, and manual means controlled by the operator for impressing current from said sources on said trunk to selectively operate said alternating current relays.

11. In a telephone system, first and second offices, an operator's position at said first office, a line terminating at said second office, a trunk interconnecting said offices, 65 automatic switches at said second office, means at said first office for controlling said automatic switches over said trunk to interconnect said trunk and said line, a source of current, a coin disposal magnet associated with said line, a source of alternating current at said first office, means for connecting said alternating current source to said trunk, and a relay responsive to alternating current received over said trunk from 70 said source for connecting said first mentioned source of current to said line to control said magnet.

In witness whereof, I hereunto subscribe my name this 21st day of December A. D., 1920.

HENRY L. HOFFMANN.
